ELECTROMECHANICAL SIGNAL TRANSLATING APPARATUS

Leslie J. Anderson, Haddonfield, N. J., assignor to
Radio Corporation of America, a corporation of
Delaware

Application October 31, 1940, Serial No. 363,632

8 Claims. (Cl. 179—115)

This invention relates to electro-mechanical signal translating apparatus, and more particularly to a reversible unit of the type adapted to either generate signal voltages in response to applied acoustical energy or to set up acoustical vibrations in response to applied signal voltages.

The principal object of my present invention is to provide an improved unit of this type which is extremely rugged in construction without sacrifice of output level.

More particularly, it is an object of my present invention to provide an improved signal translating device of this type which is particularly useful as a microphone for picking up and translating speech with good efficiency.

Another object of my present invention is to provide an improved signal translating device of the type set forth in which the mass of the moving parts is reduced to a minimum.

A further object of my present invention is to provide an improved signal translating device as aforesaid which, when used as a microphone, will not be appreciably subject to the disturbing effects of wind and low frequency noises which may be present.

It is also an object of my present invention to provide an improved reversible signal translating device as described above which is relatively simple in construction and highly efficient in use.

In accordance with this invention, I employ a sound powered telephone unit and couple to the diaphragm thereof an acoustic network so proportioned that a substantially flat frequency response is obtained over the desired range. The diaphragm is coupled through a coupling of small mass to a suitable reversible electro-mechanical unit, such as a magnetic motor or generator, as the case may be, the diaphragm being mounted in a casing having a front plate and a back plate and being spaced from said plates whereby an air space is provided both in front of and behind the diaphragm. Both of the aforementioned plates are provided with one or more openings which constitute acoustic paths between said air spaces and the exterior of said casing, the openings being preferably covered by silk or other suitable material constituting an acoustical resistance, and one or more of the openings in the back plate behind the diaphragm may be covered by an enclosure providing a small chamber. Coupled to the back plate of the diaphragm casing is a housing which encloses the reversible unit and the aforementioned enclosure, the openings in said back plate affording communication between the air space behind the diaphragm and the interior of said

housing. A tubular member extending into the housing from one of the walls thereof affords communication between the air in the housing and the atmosphere. For best results, I have found that the following general constants are desirable:

(a) The length and diameter of the tube which connects the atmosphere with the interior of the housing is preferably so chosen that the mass of air therein resonates with the compliance of the air in the housing at the lowest frequency at which transmission is desired.

(b) The resonance of the mass of the complete moving system consisting of the diaphragm, the armature of the electro-magnetic unit, and the coupling member therebetween with the compliance of this system is placed as high in frequency as will allow the desired low frequency response.

(c) The compliance of the volume of air in the space behind the diaphragm, that is, between the back surface of the diaphragm and the back plate of its casing, is made small enough so that, in combination with the mass and compliance of the moving system, resonance will be obtained at the highest frequency desired.

(d) The compliance of the "resonator volume," or the volume of air in the small chamber or chambers behind one or more of the openings in the back plate of the diaphragm casing is preferably so chosen that, in combination with the compliance of the air in the space between the back of the diaphragm and the back plate of its casing, the compliance of the moving system, and the mass of the moving system, resonance will occur about midway between the resonance points specified in (b) and (c) above.

(e) The mass of air in the chamber covered openings in the back plate of the diaphragm casing and the compliance of the air volumes in the associated chambers are preferably also made to resonate at the highest frequency desired.

(f) The mass of air in the opening or openings in the front wall of the diaphragm casing and the compliance of the volume of air in the space between this front wall and the front surface of the diaphragm are then selected to resonate at the high frequency end. This has the effect of removing the excessive peak otherwise obtained.

(g) The values of the acoustical resistance behind the one or more openings in the front plate of the diaphragm casing, the acoustical resistance behind the aforementioned tubular member, the acoustical resistance behind the one or more openings in the back plate of the diaphragm casing, and the acoustical resistance behind the cham-

ber covered opening or openings in the back plate of the diaphragm casing are then all adjusted or selected to obtain the desired frequency response, which is preferably assumed to be as flat as possible.

The novel features that I consider characteristic of my invention are set forth with particularity in the appended claims. The invention itself, however, both as to its organization and method of operation, as well as additional objects and advantages thereof, will best be understood from the following description of one or more embodiments thereof, when read in connection with the accompanying drawings, in which

Figure 1 shows a central sectional view of one form of my invention.

Figure 2 is a sectional view taken on the line II—II of Figure 1.

Figure 3 is an enlarged, detail, sectional view of a portion of the coupling member between the diaphragm and the armature.

Figure 4 is a fragmentary sectional view taken on the line IV—IV of Fig. 2.

Figure 5 is an electrical wiring diagram showing the electrical analogue equivalent to the acoustical system of the structure shown in Figures 1 and 2, and

Figures 6 to 9, inclusive, are response curves showing how the output characteristics vary by proper selection of the values of mass, compliance and resistance as discussed above.

Referring more particularly to the drawings, wherein similar reference characters designate corresponding parts throughout, there is shown, in Fig. 1, a diaphragm 1 within a casing 3 having a front plate 5 and a back plate 7, the diaphragm being suitably clamped at its periphery within the casing 3 in spaced relation to the walls 5 and 7 thereof whereby to provide a front air space 9 between the front casing wall 5 and the front surface of the diaphragm 1 and a back space 11 between the back wall 7 and the rear surface of the diaphragm 1. The front wall 5 of the diaphragm casing is provided with one or more openings 13 for establishing communication between the air space 9 and the atmosphere, and the back wall 7 is provided with a plurality of openings 15 which are disposed symmetrically about the diaphragm axis and serve to establish communication between the back air space 11 and the exterior of the casing 3. In the particular modification disclosed, only one opening 13 is shown in the front plate 5 and the three openings 15 are shown in the back plate 7, but it will be obvious that any desired number of openings may be employed in either of the plates 5 or 7 for establishing communication between the interior and the exterior of the casing 3 on both sides of the diaphragm 1. If desired, there may also be provided a perforated disk or grid 17 behind the front plate 5 to protect the diaphragm 1 from accidental injury. The openings 13 and 15 are all covered by a layer of foraminated material 19, such as silk, constituting an acoustic resistance to the passage of sound waves through the openings 13 and 15, the silk layer associated with the opening 13 being shown immediately behind the grid 17 in the particular modification shown in the drawings.

The back plate 7 is formed with an internally threaded, hollow extension 23 with which another opening 25 through the back plate 7 communicates, a plug 27 being threaded into the extension 23 to form a cavity or chamber 29 behind the

opening 25, and a layer of silk 19 being also placed behind the opening 25 similar to the openings 15. A coil spring 31 in the chamber 29 serves to hold the associated silk layer 19 against the opening 25 when the plug 27 is screwed into position.

The casing 3 is preferably molded of a suitable plastic material and has secured to its back plate 7 a reversible electro-mechanical unit 33 for co-operation with the diaphragm 1. The unit 33 includes an operating coil 35 between a pair of pole pieces 37 to which flux is supplied by a pair of magnets 38, one of the pole pieces being preferably molded integrally with the back plate 7, and the other being molded integrally with a supporting member 39 which may be of the same material as the casing 3, the pole faces of the pole-pieces 37 being suitably ground after the molding operation. Thereafter, the supporting member 39 is mounted on the back plate 7 by means of a plurality of screws or the like 41, a pair of washers 43 being employed on either side of an armature 45 to accurately center the armature in the air-gaps between the pole pieces 37.

The armature 45 constitutes the active element of the electro-mechanical device 33 and is coupled to the diaphragm 1 by a pair of light, telescopic members 47 and 49, the former of which is provided with an enlarged head 47a and the latter of which has an enlarged head 49a, as clearly shown in Fig. 3. The diaphragm 1 is provided with an opening 1a of a diameter substantially equal to the internal diameter of the member 47, and the member 49 fits through the opening 1a and is slidably received within the tubular member 47, the area of the diaphragm immediately surrounding the opening 1a being clamped between the heads 47a and 49a. Preferably, the pin or central member 49 is coated with a suitable cement prior to insertion into the tube 47, and its head may be heated with a soldering iron to cause the cement to bond the members 47 and 49 firmly to each other and to the diaphragm 1. The coupling tube 47 and the pin 49 are preferably made of aluminum, for lightness, and also preferably pass through a rubber seal 50 on the back plate 7.

By forming the reversible unit 33 and the coupling member 47—49 between its armature 45 and the diaphragm 1 in the manner above described, there is provided, first, a vibratory system constituted by the armature 45, the coupling member 47—49, and the diaphragm 1 which is of minimum mass, a condition essential to the high efficiency of my improved translating device. Furthermore, mounting the pole pieces on the back plate 7 and the supporting member 39 and thereafter assembling them in the manner heretofore described after grinding the two pole faces of each of the pole pieces 37 along a common plane not only insures an air gap of desired width, but avoids setting up strains in the armature which, in conventional telephone units, causes an initial set to take place in the armature with a tendency to throw it initially off center and thus introduce distortion. Also, the use of a synthetic resin or other plastic material for the case 3 and the supporting member 39 in the manner described eliminates the proximity of metal parts near the varying flux, and thus eddy current losses are eliminated, while grinding of the pole piece faces after they have been molded in place assures proper lining up of the pole faces, so that, with the aid of the washers 43, accurate adjustment of the air gaps can be maintained.

Secured to an annular flange 3a on the back

plate 7, as by means of a clamping ring 51, is a housing 53 in which the translating device 33 and the extension 23 and its associated plug 27 are all enclosed. The housing 53 is preferably provided with an opening 55 in the wall thereof, a tubular member 57 being fitted into the opening 55 and extending radially inwardly of the housing 53. As in the case of the openings 13, 15 and 25, a layer of silk or the like 19 may be placed over the inner end of the tubular member 57.

Figure 5 shows an electrical wiring diagram corresponding to the acoustical system heretofore described. If, in the acoustical system, it is assumed that

C_1 is the compliance of the air in the housing 53, C_2 is the compliance of the air in the back space 11,

C_3 is the compliance of the air in the "resonator chamber" 29,

C_4 is the compliance of the air in the space 9,

C_5 is the compliance of the whole moving or vibratile system consisting of the diaphragm 1, the armature 45 and the coupling therebetween 47-49,

M_1 is the mass of air in the tube 57,

M_2 is the mass of air in the openings 15,

M_3 is the mass of air in the opening 25,

M_4 is the mass of air in the opening 13,

M_5 is the mass of the entire vibratile system, R_1 is the acoustic resistance provided by the silk screen at the end of the tube 19,

R_2 is the acoustic resistance offered by the silk screen behind the openings 15,

R_3 is the acoustic resistance offered by the silk screen behind the opening 25, and

R_4 is the acoustic resistance offered by the screen behind the opening 13 (or the grid 17), as the case may be,

then the relation of the system will be as shown in the electrical analogue of Fig. 5.

It will be obvious, from an inspection of Fig. 5, that the response characteristic of the system can be altered by changing the values of the various inductances, resistances, or capacitances. I have found that, for a speech microphone, the following general constants are desirable:

(a) By proper selection of the length and internal cross-section, or diameter, of the tube 57, the mass of air therein, as represented by the inductance M_1 in Fig. 5, can be made to resonate with the compliance C_1 of the air in the housing 53 at the lowest frequency at which transmission is desired. In one particular microphone, this frequency is approximately 200 cycles. It has been found that this cut-off frequency detracts very little from the intelligibility of speech and greatly reduces the effect of wind and low frequency noise which may be present.

(b) The resonance of the mass M_5 of the whole vibratile system with the capacitance C_5 of this system should be made as high in frequency as will allow the desired low frequency response.

(c) The compliance C_2 of the air in the space 11 is made so small that, in combination with the mass and compliance of the vibratile system, M_5 and C_5 , respectively, resonance will be obtained at the highest frequency which it is desired to transmit.

(d) The value of the capacitance C_3 of the air in the "resonator chamber" 29 is preferably so chosen that, in combination with the compliance C_2 of the air in the space 11, the compliance C_5 of the vibratile system, and the mass

M_5 of the vibratile system, resonance will occur at a frequency which is about midway between the highest and lowest frequencies which it is desired to transmit by the unit.

5 (e) The mass M_3 of air in the opening 25 and the compliance C_3 of the air in the "resonator chamber" 29 are also made to resonate at the highest frequency which it is desired to transmit.

(f) The mass M_4 of air in the opening 13 and the compliance of the air in the space 9 are then made to resonate at the high frequency end to remove the excessive peak which would otherwise be attained.

(g) The values of the acoustic resistances R_1 , R_2 , R_3 and R_4 are then adjusted to obtain the desired frequency response, which, in the particular case illustrated, is assumed to be as flat as possible.

Fig. 6 shows a response curve for the system 20 without the resistances R_1 , R_2 and R_3 , the various peaks at the frequencies f_1 , f_2 , f_3 and f_4 resulting from the various portions of the system designated by the corresponding masses, compliances and resistances appended to the individual peaks.

25 By adding the resistances R_1 , R_2 and R_3 of appropriate value, the response curve of Fig. 7 will result. It will be noted that the output of the system is then represented by a much flatter response curve throughout the range up to frequency f_3 , the peak at frequency f_4 still remaining.

30 However, the peak at the frequency f_4 can be reduced considerably (as in Fig. 8) by properly selecting the values of M_4 and C_4 , that is, by making the opening 13 and the air space 9 of proper dimensions, and the response curve may be made substantially flat, finally, by proper selection of the values of M_2 and R_2 to provide a response such as shown in Fig. 9.

In practice, I have found that it is very desirable 40 to have the openings 15 formed in the back plate 7 behind the central portion of the diaphragm 1, which executes a nearly piston-like motion. Furthermore, as pointed out heretofore, the openings 15 should preferably be uniformly

45 and symmetrically spaced around the center of the diaphragm. If the openings 15 are not placed symmetrically with respect to the center of the diaphragm, or if they are formed in the plate 7 behind a region adjacent the periphery of the diaphragm, it has been found that the diaphragm has a tendency to rock which, in turn, produces rather erratic response curves. For the foregoing reasons, therefore, it is essential that the openings 15 be properly located.

55 Although I have shown and described but a single embodiment of my invention, it will be apparent to those skilled in the art that many modifications thereof are possible. Accordingly, I desire it to be understood that my invention 60 is not to be limited except insofar as is made necessary by the prior art and by the spirit of the appended claims.

I claim as my invention:

65 1. In signal translating apparatus, the combination of a casing having a front wall and a back wall, a diaphragm in said casing in spaced relation to each of said walls whereby to provide front and back air spaces, respectively, in front of and behind said diaphragm, signal translating

70 means exterior to said casing and including an active element, means coupling said element to said diaphragm for movement in unison, and a housing coupled to said back casing wall and enclosing said translating means, said front casing wall having at least one opening extending there-

through and affording communication between said front space and the atmosphere, said back casing wall having at least one opening extending therethrough and affording communication between said back space and the interior of said housing, and said housing having at least one opening extending through a wall thereof and affording communication between the interior of said housing and the atmosphere.

2. The invention set forth in claim 1 characterized in that each of said openings is covered by a foraminous material constituting an acoustic resistance to the passage of sound waves therethrough.

3. The invention set forth in claim 1 characterized by the addition of an open ended tubular member extending inwardly of said housing through the opening therein whereby communication between the interior of said housing and the atmosphere is through said tubular member.

4. The invention set forth in claim 1 characterized by the addition of an open ended tubular member extending inwardly of said housing through the opening therein whereby communication between the interior of said housing and the atmosphere is through said tubular member, and characterized further in that said tubular member is of such length and internal cross-sectional area that the mass of air therein resonates with the compliance of the air in said housing at substantially a predetermined low frequency such that said low frequency will be substantially the lowest frequency that said apparatus will translate.

5. The invention set forth in claim 1 characterized by the addition of an open ended tubular member extending inwardly of said housing through the opening therein whereby communication between the interior of said housing and the atmosphere is through said tubular member, and characterized further in that the openings in both said casing walls and the inner end of said tubular member are all covered by a foraminous material constituting an acoustical resistance to the passage of sound waves therethrough.

6. In signal translating apparatus, the combination of a casing having a front wall and a back

wall, a diaphragm in said casing in spaced relation to each of said walls whereby to provide front and back air spaces, respectively, in front of and behind said diaphragm, signal translating means exterior to said casing and including an active element, means coupling said element to said diaphragm, said front casing wall having at least one opening extending therethrough and affording communication between said front space and the atmosphere, said back casing wall having at least two openings extending therethrough, at least one of said last named openings affording communication between said back space and the exterior of said casing, means on said back wall behind the other of said openings therein providing a closed chamber therebehind, said last named opening affording communication between said chamber and said back space, and a housing coupled to said back plate and enclosing said translating means and said chamber providing means, said housing also having an opening extending through a wall thereof and affording communication between the interior of said housing and the atmosphere.

7. The invention set forth in claim 6 characterized by the addition of a tubular member extending through said housing wall opening into the interior of said housing whereby communication between the interior of said housing and the atmosphere is through said tubular member.

8. The invention set forth in claim 6 characterized by the addition of a tubular member extending through said housing wall opening into the interior of said housing whereby communication between the interior of said housing and the atmosphere is through said tubular member, and characterized still further by the addition of a cover of foraminous material over all of the openings in each of said casing plates and over the inner end of said tubular member, said foraminous covers constituting acoustical resistances to the passage of sound waves through said openings and through said tubular member, and the values of said acoustical resistances being such as to give a substantially flat response characteristic to said apparatus.

LESLIE J. ANDERSON.
